CONVEYER CHAIN FOR CANNING APPARATUS.

1,418,572.

Specification of Letters Patent. Patented June 6, 1922.

Application filed February 9, 1921. Serial No. 443,549.

To all whom it may concern:

Be it known that we, SIMES T. HOYT and JOHN S. NAPIER, citizens of the United States, residing at Honolulu, Territory of Hawaii, have invented certain new and useful Improvements in Conveyer Chains for Canning Apparatus; and we do hereby declare the following to be a full, clear, and exact description of the invention, such as

10 will enable others skilled in the art to which it appertains to make and use the same.

This invention relates to improvements in conveyer mechanism for canning apparatus, and particularly to a conveyer chain construction adapted for use in conjunction with a double-track arrangement, whereby lateral extensions of the chain proper are designed to engage one or more cans positioned on said tracks and cause them to be carried 20 or rolled along with the movement of said chain.

It is frequently convenient, in canning apparatus, to cause the cans to roll on tracks or runways so disposed that the cans will 25 not roll as desired by gravity, and in such cases the herein described device is particularly applicable, whereby a movable chain, adapted to run over sprockets, is provided with lateral arms or projections which will 30 extend over the tracks and cause the cans to be conveyed or rolled along said tracks. In this connection, it has been found highly desirable to have a chain in which these lateral projections are at all times in the center line 35 of the chain which produces satisfactory results in causing the cans to roll on the tracks in the manner herein set forth.

The principal object of the invention is to produce a device of the character indicated, 40 simple in construction and design, and one that is well adapted to any of the various types of canning apparatus or the like, where it is desired to manipulate the cans in the manner stated, said device being particularly 45 applicable to the continuously operated canning apparatus of either the cooker or cooler type, forming the subject matter of a co-pending application, filed March 28th, 1921, Serial No. 456,147.

50 A further and important object of the in-

vention is the provision of a type of chain particularly adapted to the canning apparatus as disclosed in the co-pending application above referred to. In this especial form of canning apparatus a conveyer chain is 55 adapted to travel continuously from one flight to the next higher flight, running over sprockets arranged at the opposite ends and between each flight, the conveyer chain travelling along each flight in opposite directions. This reversing of the direction of travel of the continuous chain in the manner aforesaid causes a turning over, or a reversing of the chain itself, or, in other words, what would be the top of the chain 60 on one flight, would be the bottom of the chain on the next succeeding flight. It is highly desirable that the laterally extending arms of the chain at all times engage the center line of the cans to cause the correct 65 movement of the cans along each flight. These various desired results are accomplished by the particular type of chain herein illustrated and described, whereby the laterally extending arms are at all times 70 maintained in suspended relation with respect to the longitudinal center line of the chain, which is the only portion of said conveyer chain which is supported in its course 75 round the respective sprockets and flights. 80

Generally stated, the invention comprises a conveyer chain of the type commonly used in connection with sprockets and the like, wherein certain selected pintles or connecting pins, forming the connections between the links, are elongated or extended laterally of the chain to either one or both sides thereof to form arms overhanging one or more trackways along which cans and the like are conveyed, the arms adapted to engage the 90 cans causing them to roll or be carried along the trackway with the movement of the chain. These laterally disposed arms at their point of contact with their respective cans are further provided with anti-frictional rollers, preferably of larger diameter than the arm, so that said rollers will not only materially reduce the friction between the cans and the arm but will also prevent the arms from coming in contact with the 95

rims of the cans, thereby preventing the injury of the cans at these points.

The preferred embodiment of the invention is illustrated in the accompanying drawings, in which—

Fig. 1 is a plan view, illustrating the improved conveyer chain construction,

Fig. 2 is a view, partly in section and partly in elevation, showing the conveyer chain in operative relation with respect to the cans and the preferred double-track construction.

Fig. 3 is a view, partly in section and partly in side elevation, of the arrangement shown in Fig. 2, and

Fig. 4 is an enlarged detailed view of a portion of Fig. 1, illustrating the means of securing the rollers on the ends of the laterally disposed arms of the chain.

Referring to the drawings in detail, the preferred form of chain in connection with which the invention is illustrated, comprises a sprocket chain of substantial pattern well adapted for the work indicated, consisting of associated links 1, inter-connected by pintles or connecting pins 2 in any improved manner, one end of each link having inwardly extending portions 3 forming journals or the like, upon which are mounted the customary roller bearings 4, for engaging with the supporting sprockets, not shown.

In adapting the invention to the type of chain indicated, according to the intervals desired, there are provided laterally extending arms 5, formed as a continuation of the pintles or connecting pins 2 of the contiguous links 1. These lateral arms 5 may either be formed on each connecting pin, alternate pins, or at any convenient spacing as desired, but the alternate arrangement, as shown, has been found most useful and efficient in connection with the particular form of apparatus, aforesaid. These lateral arms 5 are preferably formed integral with their associated connecting pins and extend to the desired distance on either or both sides of the chain. Near the outer end of one of the lateral extensions of each arm is provided an annular flange 6, forming a stop or side bearing for the roller 7 journalled on that end of said arm. The roller 7 is locked on this extension in this position by a split retaining washer 8, inserted in diametrically opposite grooves 9, formed in the end portion of said arm 5 adjacent the outside end of the roller 7, leaving sufficient play for the rotation of said roller. On the oppositely disposed extension of each arm the roller 7 is rotatably mounted between two split retaining washers 8, as shown in Fig. 3.

After being inserted in the grooves 9, the open ends of said washer 8 are bent inwardly around the arm, as clearly shown in Fig. 4, thereby locking said washer in its proper po-

sition. These rollers 7, as shown, are of somewhat greater diameter than the arms 5 and form the means of contact at these points with the cans being conveyed, thus materially reducing the friction and also preventing the arms from coming in contact with and rubbing on the rims of the cans, which are the weakest places thereon.

The invention as illustrated is applied to the conventional type of chain construction which may be of any of the approved shapes adapted for use with sprockets or the like, well known in the art, the particular design and precise shape or dimensions of the chain forming no part of the invention, and the same is not to be restricted thereto.

What we claim is:

1. In a conveyer, the combination with a track-way, of a conveyer chain comprising a series of contiguous links, pivot pins connecting said links, lateral extensions formed on said pivot pins over-hanging said track-way, said chain in operative position being supported in a plane above the plane of the track-way.

2. In a conveyer, the combination with parallel track-ways, of a conveyer chain comprising a series of contiguous links, pivot pins connecting said links, oppositely disposed lateral extensions formed on certain pivot pins spaced at regular intervals over-hanging said track-ways, said chain in operative position being supported in a plane above the plane of the track-way.

3. In a conveyer, the combination of parallel track-ways adapted to receive a series of rolling cans, of a conveyer chain comprising a series of contiguous links, pivot pins connecting said links, oppositely disposed lateral extensions formed on alternately spaced pivot pins overhanging said track-ways, and adapted to engage the cans thereon, said chain in operative position being supported in a plane above the plane of the track-ways, whereby the lateral extensions thereof will engage the center line of the cans.

4. In a conveyer the combination with parallel superposed continuous track-ways adapted to receive a series of rolling cans, of a chain adapted to convey said cans along said track-way from one flight to the next, comprising a series of contiguous links, pivot pins connecting said links, oppositely laterally extending arms, formed integral with alternately spaced pivot pins, overhanging said track-ways, rollers carried by said arms adapted to engage the cans on the track-ways, said chain in operative position being supported in a plane above the plane of the track-ways, whereby the lateral extensions thereof will at all times engage the center line of the cans, even though said chain is reversed during its course from one flight to the next.

5. A conveying chain for a parallel row engage the center line of their respective of cans or the like, comprising a series of cans during the conveying operation. In testimony whereof we affix our signatures.
- links, said chain adapted to be supported 10
5 along its longitudinal intermediate portion and relatively long suspended lateral extensions, formed on said pivot pins adapted to
